(57) **CLAIM**

The ornamental design for a vented skylight, as shown and described.

DESCRIPTION

FIG. 1 is a front top right isometric view of the vented skylight of the present invention;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is a rear top left isometric view thereof; and,

FIG. 9 is a bottom isometric view thereof.

The portion of the vented skylight that are illustrated in broken lines form no part of the claim for the vented skylight.
